ATTORNEY

UNITED STATES PATENT OFFICE.

CLARKE P. POND, OF OLENA, OHIO.

BRIDLE-BIT.

SPECIFICATION forming part of Letters Patent No. 416,422, dated December 3, 1889.

Application filed June 20, 1889. Serial No. 315,010. (No model.)

To all whom it may concern:

Be it known that I, CLARKE P. POND, of Olena, in the county of Huron and State of Ohio, have invented a new and useful Improvement in Bridle-Bits, of which the following is a specification.

My invention relates particularly to an improved bridle-bit which is intended to remedy and prevent side pulling, a fault common to horses, and generally caused by one side of the mouth being tougher than the other; and with this object in view my invention consists of a bit having the ends of the bar or mouth-piece differently shaped or surfaced, one end being smooth or soft and adapted to be held on the tender side of the mouth, while the other end is roughened or hardened and intended to be held in the tough side of the mouth.

Referring to the accompanying drawings, Figure 1 is a perspective view of my improved bit, and Figs. 2 and 3 are modifications of the same.

In carrying out my invention I employ a bit A the bar or mouth-piece of which may be straight or snaffle, as desired, and is provided with the usual rings *a a* at each extremity for attaching the reins. One side or end B of the bar is intended to be inserted and carried in the tender side of the horse's mouth, and to prevent or decrease the pain is usually formed round, as shown in the drawings. If desired, this end may be of any desired form and covered with some soft material *b*, such as leather or rubber, or the end itself may be of these materials.

The opposite side or end C, which is intended to be carried in the tough side of the mouth and irritate the same, is usually constructed of some hard material and roughened. This roughness may be formed by making the end square or rectangular in cross-section, or it may be twisted or barbed,

or it may be of the usual form and covered with some hard and roughened material. If 45 desired, the end C may be made of wire and the end B may be increased in diameter, so as to form a broader bearing for the tender side and relieve the pain, or the opposite end may be reduced, all of which constructions will 50 tend to bring the horse's head around straight and prevent side pulling, which is not only disagreeable to the driver, but also gives the horse a very ugly appearance.

The construction of my improved bit being 55 very plain and simple, its operation is very easily understood. Where a horse is addicted to side pulling it is evident that the side of his mouth with which he pulls the most is the tougher, and to prevent this turning of the head it is only necessary to replace the ordinary bit by one constructed as shown and described, care being taken to see that the hard and roughened end is placed on the tough side of the mouth, while 60 the soft or smooth side is carried in the tender side.

Having thus described my invention, what I claim as new, and desire to secure by Letters Patent, is—

1. An improved bridle-bit the bar or mouth-piece of which has one end or side round and smooth, and its opposite side or end provided with corrugations, sharp edges, or projections, as and for the purpose described.

2. An improved bridle-bit the bar or mouth-piece of which has one end or side covered with soft or elastic material and its opposite side or end of hard material and provided with sharp edges or projections, as and for 80 the purpose described.

CLARKE P. POND.
